UNITED STATES PATENT OFFICE.

HENRY HERMAN WESTINGHOUSE, OF NEW YORK, N. Y.

ANTISLIPPING STARTING DEVICE FOR STEAM LOCOMOTIVES.

Application filed July 18, 1922. Serial No. 575,912.

To all whom it may concern:

Be it known that I, HENRY H. WESTINGHOUSE, a citizen of the United States, and a resident of New York, in the county and State of New York, have invented a certain new and useful Antislipping Starting Device for Steam Locomotives, of which the following is a specification.

This invention relates to an anti-slipping starting device for steam locomotives. It is well known that difficulty is experienced in putting heavy trains in motion under certain conditions of grades, curvature of track, and other causes tending to increase resistance to starting, and it often becomes necessary to resort to the expedient of taking slack to enable the locomotive to attain sufficient headway to overcome this heavy resistance, resulting, however, in the production of destructive strains and shocks in the equipment and great discomfort to passengers. This objectionable practice is resorted to because of the inability of the locomotive to otherwise effectively exert sufficient tractive power to start the train. If no preliminary free motion is available when the locomotive is required to overcome more than the average resistance to starting, the application of the full steam pressure to the driving wheels causes excessive slippage, which greatly reduces the adhesion between the wheel and the rail, and proportionately the tractive effort of the locomotive. In order to obtain the full tractive power of the locomotive, it is necessary to maintain maximum adhesion between the driving wheels and the rails, by limiting the permissible rate of slippage of the driving wheels upon the rails to a degree that does not seriously reduce adhesion. A slow rate of slippage does not materially decrease adhesion, and in fact under some conditions may increase it. The main object of my invention, therefore, is to maintain the maximum tractive effort of the locomotive by positively preventing such a rate of rotation of the driving wheels as will impair or materially reduce adhesion between the driving wheels and the rails.

Various forms of mechanism and driving

connections may be devised for accomplishing these results within the scope of my invention, which is not limited to any specific construction, but contemplates the use of a suitable restraining or governing transmission mechanism, preferably connected to a main driving axle of the locomotive, for preventing such rate of rotation or acceleration as would destroy adhesion, and cause material slippage, but permitting a movement of the drivers under which the tractive adhesion will be maintained.

According to another feature of my invention, a suitable auxiliary actuator may be connected to the restraining transmission mechanism for operating the same at a suitable speed, thereby governing and determining the speed at which the drivers may revolve under the power of the main engine.

According to another feature of my improvement, suitable means are provided for connecting and disconnecting the restraining mechanism, that is for throwing the same into and out of operation, as desired. As it may not be desirable to permit the throwing in of said mechanism when the locomotive is running, means are provided for preventing such action, and this comprises a further feature of the invention. Means are also provided for automatically disconnecting the restraining mechanism when a certain speed of the engine is attained.

A suitable form of transmission mechanism having the desired characteristics of restraining and governing the rate of rotation of the drivers, is a worm driving gear, and I have illustrated my invention with this type of construction in the accompanying drawings, in which Figure 1 is a vertical section of one form of apparatus embodying my improvement, and applied to an axle of a locomotive; Fig. 2, a view of the same, partly in plan and partly in horizontal section, on the line 2-2 of Fig. 1; Fig. 3, a diagrammatic view, in elevation, showing the same applied to a locomotive; Fig. 4, a side elevation of the worm and gear wheel; Fig. 5, a horizontal section of the auxiliary

motor or actuator and casing taken substantially on the line 5—5 of Fig. 1; and Fig. 6 an elevational view of a locomotive showing my invention applied thereto.

5 According to the construction shown, I employ an auxiliary motor, 10, which may be termed an actuator and which may be of any suitable type, preferably a high speed motor, such as a steam engine, and having 10 its shaft, 11, provided with a worm, 12, meshing with gear wheel, 13, mounted on an axle, 14, which may preferably be one of the driving axles of the locomotive. The 15 motor and gearing may be enclosed within a casing, 15, rotatably supported upon the axle, and adapted to contain oil for the lubrication of gearing. For holding the casing in its upright position, and yielding 20ingly balancing the same upon the axle, I have shown, in Fig. 3, a lever, 16, pivotally attached at one end to said casing, and mounted on a fixed fulcrum, 17, secured to some portion of the locomotive. A spring, 18, acts upon the other short end of the 25 lever, 16, to balance the overhung weight of the casing upon the axle. The fixed fulcrum 17 being secured to a portion of the locomotive, it will be evident that the axle carrying the auxiliary driving mechanism is 30 relieved of part of the weight of said mechanism, which is thus distributed to the other driving wheels.

The auxiliary actuator is preferably mounted upon hollow trunnions within the 35 casing, 15, and the supply of steam or other fluid for operating the motor may be admitted through the one trunnion and discharged through the other. The actuator is provided with an extension frame, 19, having 40 bearings for the motor shaft, 11, carrying the worm, 12, and the latter is normally held out of engagement with the gear, 13, by means of a spring, 20, which acts to swing the actuator upon its trunnions sufficiently to throw the worm out of engagement. 45 For the purpose of throwing the worm into engagement when it is desired to operate the auxiliary actuator to assist in starting, a fluid pressure actuated device 50 may be employed comprising a piston, 21, operating a cam or lever, 22, adapted to bear upon the frame, 19, and force the worm, 12, into engagement with the wheel, 13, thereby 55 swinging the actuator upon its trunnions, and compressing the spring, 20. A spring, 23, is employed for releasing the cam lever, 22, when the fluid under pressure is released from the piston, 21, whereupon the spring, 20, turns the actuator frame upon its pivots 60 and throws the worm out of engagement.

The worm shaft, 11, may be provided with a small rotary pump, 24, for forcing oil through a passage, 25, to lubricate the worm, 12.

65 In order to relieve the shocks upon the

gear wheel, 13, when the worm is thrown into engagement, the wheel may be of the resilient type, that is, formed with the rim portion, 13^a, as a separate part, and mounted upon a wheel with a capacity of a limited 70 relative movement, a spring, 26, being located between opposing lugs upon the rim and upon the wheel for permitting a limited yielding movement between these parts. For the purpose of facilitating the assembly 75 of the gear wheel and casing upon the axle, without the necessity of removing a driving-wheel of the locomotive, the gear wheel may be divided transversely and also diametrically, each portion being adapted to be 80 clamped upon the axle, as indicated in Fig. 2, and the casing may also be divided both horizontally and vertically, the parts having suitable flanges and adapted to be bolted together as indicated. 85

The supply pipe, 28, for furnishing a supply of steam to operate the auxiliary actuator may be connected to the boiler at any suitable point, but preferably leads from the main engine supply between the throttle 90 valve and the engine, so that steam may be supplied to the auxiliary actuator at the same time that it is being supplied to the main engine. The supply through the pipe, 28, is controlled by a fluid pressure operated valve, 33, having pipe connection, 31, with a manually operated valve, 32, in the locomotive cab, the valve, 33, being normally closed by a spring when the fluid is exhausted from the pipe, 31. The pipe, 31, 100 also connects with the cylinder of the piston, 21, for throwing the worm gear into engagement. A volumetric reservoir, 37, may also communicate with the pipe, 31, for furnishing an additional volume of air under pressure to act upon the devices, 21 and 33, and compensate for slight leakage which may occur when the auxiliary actuator is operating.

The auxiliary actuator may be provided with a governor device, 27, having an operating connection, 29 and 30, with a pressure relief valve, 34, and adapted, when a certain speed of the actuator is attained, to open the valve, 34, and release the pressure 115 from the devices, 21 and 33, whereby the auxiliary actuator will be automatically thrown out of operation.

The engineman's operating valve, 32, is preferably of the self closing type, so that after a full supply of fluid, such as compressed air, has been admitted to the volumetric reservoir and actuating cylinders of the piston, 21, and valve, 33, it will be automatically returned to closed position. 120

125 As it may be important to prevent any attempt to throw the worm into engagement with the worm gear wheel after the wheel has started to move, I have indicated means for preventing this, comprising a governor 130

- mechanism 36, operated by the rotation of the gear wheel, 13, or axle, 14, and having operating connections of any suitable type for closing a valve, 35, in the supply pipe, 31, so that said valve shall be closed whenever the gear wheel is moving, but open at other times. In this way, it will be impossible for the engineman to operate his valve, 32, to supply air to the piston, 21, to throw the worm into engagement with the worm wheel when the latter is turning.
- 10

When it is desired to put the locomotive in motion, the valve, 32, will be opened to charge the volumetric reservoir, 37, and actuate devices, 21 and 33, to throw the worm into engagement with the worm wheel and open supply pipe, 28. Then when the main throttle is opened to supply steam to the steam engines, steam will also flow to the auxiliary actuator, causing rotation of the driving wheels at a rate of speed determined by the speed of the auxiliary actuator. This rate will not exceed that required to maintain maximum tractive power of the locomotive. Any tendency of the drivers to attain slipping speed, due to excess of power applied by the main engine, will be restrained by the resistance of the worm wheel and the actuator. When the locomotive has attained the desired predetermined speed, the governor device 27, will open release valve, 34, thereby effectively closing supply valve, 33, and throwing the worm out of operative engagement with the worm wheel. The auxiliary actuator may therefore be automatically thrown out of operation, or, at any time, by a manually-operated release valve such as 38, if desired.

Having now described my invention, what I claim as new and desire to secure by Letters Patent is:

1. In a locomotive starting device, the combination with the main engine, drivers, and positive driving connections from the engine to said drivers, of a positive restraining mechanism operatively associated with the drivers and wholly carried by and movable with the locomotive, and acting to prevent such a rate of rotation of the same relative to the speed of the locomotive as to cause material slippage of the drivers.

2. In a locomotive starting device, the combination with the main engine, drivers, and positive driving connections from the engine to said drivers, of a positive restraining mechanism operatively associated with the drivers and carried in its entirety by the locomotive, and acting to prevent such a rate of rotation of the same relative to the speed of the locomotive as to cause material slippage of the drivers, and means for connecting and disconnecting said mechanism.

3. In a locomotive starting device, the combination with the main engine, drivers, and positive driving connections from the

engine to said drivers, of a worm gear mechanism operatively associated with the drivers, and acting to prevent such a rate of rotation of the same as to cause material slippage of the drivers.

70

4. In a locomotive starting device, the combination with the main engine, drivers, and positive driving connections from the engine to said drivers, of a worm and gear mechanism operatively associated with the drivers, and means for throwing said worm into and out of engagement with the gear.

75

5. In a locomotive starting device, the combination with the main engine, drivers, and positive driving connections from the engine to said drivers, of a worm and gear mechanism operatively associated with the drivers, and a fluid pressure operated device for throwing said worm into engagement with the gear.

80

6. In a locomotive starter, the combination with the main engine, driving wheels, and positive driving connections from the engine to said drivers, of an auxiliary motor, a worm driven by said motor, a gear wheel having a driving connection with an axle, and means for throwing the worm into and out of engagement with said gear.

90

7. In a locomotive starter, the combination of an auxiliary starting motor mounted on trunnions and having a shaft, a worm on said shaft, a gear wheel having a driving connection with an axle, and means for swinging said motor to throw the worm into and out of engagement with said gear.

100

8. In a locomotive starter, the combination with the main engine, driving wheels, and positive driving connections from the engine to said drivers, of an auxiliary motor, a worm gear mechanism operatively associated with the drivers and operated by said motor for assisting in starting the locomotive, and a casing enclosing said motor and gear mechanism and containing oil for lubrication of the gearing.

105

9. In a locomotive starter, the combination of a gear fixed on an axle, a casing enclosing said gear, an auxiliary motor mounted in said casing at one side of the axle, a worm driven by said motor, and means for throwing said worm into and out of engagement with said gear.

110

10. In a locomotive starter, the combination with a main engine, a pair of driving wheels, positive driving connections from the engine to said wheels, and an axle on which said wheels are mounted, of a gear fixed to said axle, a casing enclosing said gear and rotatably supported on said axle, an auxiliary motor mounted in said casing at one side of the axle and having a connection for driving the gear, and a balancing lever pivotally connected to said casing.

115

11. In a locomotive starter, the combination with the main engine, driving wheels,

120

125

130

and positive driving connections from the engine to said drivers, of an auxiliary motor, a gear mechanism operated thereby and connected with said drivers for controlling the starting of the locomotive, a fluid pressure operated device for throwing said mechanism into and out of gear, a fluid pressure operated valve for controlling a supply of fluid to said motor, and a manually operated valve for supplying fluid to said pressure operated devices.

12. In a locomotive starter, the combination with the main engine, driving wheels, and positive driving connections from the engine to said drivers, of an auxiliary motor, a gear mechanism operated thereby and connected with said drivers for controlling the starting of the locomotive, a fluid pressure operated device for throwing said mechanism into and out of gear, a fluid pressure operated valve for controlling a supply of fluid to said motor, a manually operated valve for supplying fluid to said pressure operated devices, and a speed governing actuated valve for automatically releasing fluid from said devices.

13. In a locomotive starter, the combination with the main engine, driving wheels, and positive driving connections from the engine to said drivers, of an auxiliary motor, a gear mechanism operated thereby and connected with said drivers for controlling the starting of the locomotive, a fluid pressure operated device for throwing said mechanism into and out of gear, a fluid pressure operated valve for controlling a supply of fluid to said motor, a volumetric reservoir connected to said fluid pressure operated devices, and a manually operated valve for supplying fluid thereto.

14. In a locomotive starter, the combination with the main engine, driving wheels, and positive driving connections from the engine to said drivers, of an auxiliary motor, a gear mechanism operated thereby and connected with said drivers for controlling the starting of the locomotive, a fluid pressure operated device for throwing said mechanism into gear, a supply valve therefor, and a valve means operated automatically by the movement of the vehicle for closing communication from said supply valve to said fluid pressure device.

15. In a locomotive starting device, the combination with a main engine, driving wheels, and driving connections from the engine to said wheels, of a restraining mechanism operatively associated with said driving wheels and wholly carried by the locomotive for positively opposing the driving power of the main engine against a tendency of the wheels to suddenly accelerate in speed.

16. In a locomotive starting device, the combination with a main engine, driving

wheels, and driving connections from the engine to said wheels, of a restraining mechanism operatively connected to the driving wheels and entirely contained on the locomotive for positively preventing a sudden increase in the rate of rotation of said wheels.

17. In a locomotive starting device, the combination with a main engine, driving wheels, and driving connections from the engine to said wheels, of means associated with said driving wheels and operating independently of the road bed for positively preventing a sudden acceleration in the speed of said wheels.

18. In a locomotive starting device, the combination with a main engine, driving wheels, and driving connections from the engine to said wheels, of a restraining mechanism operatively connected to said driving wheels and carried by the locomotive in its entirety for positively preventing a sudden increase in the rate of rotation of said wheels and adapted to permit a gradual increase in the rate of rotation.

19. In a locomotive starting device, the combination with a main engine, driving wheels, and driving connections from the engine to said wheels, of mechanism connected to said driving wheels and entirely contained on the locomotive and inherently capable of positively preventing rotation of said wheels by the main engine and means for operating said mechanism to permit rotation of said wheels.

20. In a locomotive starting device, the combination with a main engine, driving wheels, and driving connections from the engine to said wheels, of a restraining mechanism carried wholly by the locomotive and acting to positively prevent a sudden increase in the rate of rotation of said driving wheels, and means operable to operatively disconnect said mechanism from the driving wheels.

21. In a locomotive starting device, the combination with a main engine, driving wheels, and driving connections from the engine to said wheels, of a restraining mechanism carried wholly by the locomotive for positively preventing a sudden increase in the rate of rotation of said driving wheels, and means for operatively connecting said mechanism to and disconnecting said mechanism from said driving wheels.

22. In a locomotive starting device, the combination with a main engine, driving wheels, and driving connections from the engine to said wheels, of an irreversible worm gear mechanism associated with said driving wheels, and an auxiliary motor for driving said mechanism.

23. In a locomotive starting device, the combination with a main engine, driving wheels, and driving connections from the

engine to said wheels, of an irreversible worm gear mechanism having the gear rotatable with the driving wheels, and an auxiliary motor for rotating the worm.

5 24. In a locomotive starting device, the combination with a main engine, driving wheels, and driving connections from the

engine to said wheels, of a gear rotating with said driving wheels, a worm meshing with said gear, the pitch of the worm being such that the worm cannot be rotated by the gear, and an auxiliary motor for rotating the worm.

HENRY HERMAN WESTINGHOUSE.
